ULTRA HIGH FREQUENCY IGNITION DEVICE

Nathaniel I. Korman, Camden, N. J., assignor to
Radio Corporation of America, a corporation of
Delaware

Application August 19, 1943, Serial No. 499,294

7 Claims. (Cl. 315—39)

1

This invention relates generally to ignition systems for internal combustion engines and particularly to ignition plugs for systems employing ultra-high frequency energy suitably applied to said plugs for establishing ignition temperatures.

Present ignition systems for aircraft use have the distinct disadvantage that considerable radio interference is generated by the high potentials, by the wave form thereof, and by comparatively low frequencies involved. Numerous ignition shielding devices are known for decreasing the inherent radio interference set up by said systems, but such devices have limited utility due to wide variations in moisture, pressure and temperature gradients encountered in radio aircraft operation. For example, when an airplane flies through a cloud, considerable condensation may occur within the shielding surrounding the high tension spark plug leads, resulting in reduced efficiency of the ignition system and objectionable radio interference. Moreover, at low pressures experienced at extremely high altitudes, spark-over may occur in the ignition distribution system thereby causing engine failure. Various methods, including the use of air pumps, have been devised for exhausting the moisture or increasing the air pressure within the high tension electrostatic ignition shielding, but the additional apparatus required adds weight and has other serious disadvantages.

The instant invention is an improvement upon the system described in the copending U. S. application of Francis X. Rettenmeyer Ser. No. 445,046 filed May 29, 1942, entitled Ultra high frequency ignition system. That copending application discloses and claims an ultra-high frequency ignition system which utilizes the advantages of low inherent radiation from low impedance high frequency transmission lines or from wave guides. The wave guides couple an ultra-high frequency pulse generator to tuned sparking devices which comprise quarter wave sections of concentric transmission line. The system thus described, by utilizing ignition voltages of ultra-high frequency considerably above the normal frequencies used for radio transmission, and by employing low impedance ignition energy transmission lines, greatly reduces radio interference and provides efficient ignition under normally adverse conditions.

The instant invention comprises several embodiments and modifications thereof of ignition plugs adapted for use with wave-guide ultra-high frequency ignition distribution systems. Briefly, the various embodiments of the inven-

2

tion each comprise a cylindrical conductive member formed to receive a waveguide distribution element, and threaded to engage a threaded spark plug port in an internal combustion engine. An insulating member is disposed within a constricted portion of the cylindrical conductive member which extends into the spark plug port to provide an effective gas seal. A conductive element which is resonant at the operating ultra-high frequency is raised in temperature, or forms a spark discharge, in response to the ultra-high frequency energy of the field impressed thereon.

One embodiment of the invention includes a conductive disc including a resonant aperture of predetermined shape and dimensions to provide a spark discharge at a restricted portion of said aperture in response to impressed ultra-high frequency energy. A second modification of the invention includes a section of wave guide having a length equivalent to one half wavelength at the operating frequency and having conductive portions at each end to provide spark gaps for the ultra-high frequency energy impressed thereon. A third embodiment of the invention comprises a resonant conductive ring supported by a suitable insulating spider transversely of the constricted wave guide portion which extends into the cylinder spark plug port. Ultra-high frequency energy generates circulating currents on the surface of the resonant conductive ring which heat the surface of the ring to ignition temperatures. When the ultra-high frequency energy is not impressed upon the ring the mass thereof provides sufficient cooling by conduction from the surface portions to the interior portions thereof.

Among the objects of the invention are to provide an improved method of and means for providing ultra-high frequency ignition in an internal combustion engine. Another object of the invention is to provide an improved ultra-high frequency ignition plug for use with a wave guide type ignition distribution system. An additional object of the invention is to provide an improved ultra-high frequency ignition plug for use with a wave guide distribution system wherein a spark discharge is provided across a restricted portion of a resonant conductive element forming a portion of said plug. An additional object of the invention is to provide an improved ultra-high frequency ignition plug for use with a wave guide ignition distribution system wherein a spark discharge occurs between adjacently disposed conductive elements located at the ends of a half wave resonant portion of said plug. A

further object of the invention is to provide an ultra-high frequency ignition plug for use with a wave guide type ignition distribution system wherein the surface of a resonant conductive element is heated to ignition temperatures by circulating currents induced therein, and wherein cooling of the heated conductive element is provided by conduction from the surface portions to the interior portions thereof.

The invention will be further described by reference to the accompanying drawing of which Figure 1 is an elevational cross-sectional view of one embodiment thereof, Figures 2 and 3 are cross-sectional views of different modifications of Figure 1 taken along the section line II-II; Figure 4 is a cross-sectional elevational view of a second embodiment of the invention; Figure 5 is a sectional view of the embodiment illustrated in Figure 4 taken along the section line V-V; Figure 6 is a cross-sectional elevational view of a third embodiment of the invention and Figure 7 is a sectional view of Figure 6 taken along the section line VII-VII. Similar reference characters are applied to similar elements throughout the drawing.

Referring to Figure 1, a cylindrical conductive ignition plug 1 includes an enlarged portion 2 having slots 3 adapted to provide spring contact surfaces for receiving an ultra-high frequency ignition distribution wave guide 4. A constricted portion 5 of the ignition plug 1 includes a threaded sleeve 6 adapted to engage the threads of a conventional spark plug port of an internal combustion engine. A portion 7 of the threaded sleeve 6 may be flattened to receive a wrench for tightening the plug into the spark plug port. An insulating plug 8 is sealed within the constricted portion 5 of the ignition plug 1 to provide an effective gas seal for the internal combustion engine cylinder.

Adjacent the end of the constricted plug portion 5, remote from the enlarged plug portion 2, a conductive ignition element 9 is disposed transversely of the constricted portion 5 of the wave guide plug. A spark discharge is caused to occur across a gap 10 when the conductive element 9 is subjected to ultra-high frequency energy through the wave guide system. The ultra-high frequency energy may be pulsed and commutated to provide suitably timed pulses of ignition energy in the manner described in the aforementioned copending application.

Figure 2 illustrates the details of a typical conductive sparking element 9 as employed in the device described in Figure 1. The conductive disc 9 disposed transversely of the constricted ignition plug portion 5 includes a "resonant aperture" formed by two circular holes 11, 11' connected by a narrow slot 10. Ultra-high frequency energy in the form of an electric field in the wave guide induces circulating currents in the conductive disc 9 which provides sufficient voltage between the adjacent sides of the narrow slot 10 to provide a spark discharge across said slot in response to the pulsed and commutated ultra-high frequency energy.

Figure 3 is similar to Figure 2 with the exception that the conductive disc 9 includes two parallel disposed slots 12, 12' interconnected by a narrow slot 10. The spark discharge occurs between the closely spaced sides of the narrow slot or aperture 10 in response to voltages induced therein by circulating currents caused by ultra-high frequency energy applied thereto.

Figure 4 is similar in all respects to Figure 1 except that the conductive disc 9 is disposed transversely of the constricted portion 5 of the ignition plug 1.

with the exception that the constricted portion of the ignition plug has a length of the order of $\frac{1}{2}$ wavelength at the operating frequency. Conductive elements 13, 13', forming spark gaps 14, 14', are disposed adjacent the ends of the constricted plug portion 5. Ultra-high frequency energy applied to the constricted plug portion induces voltages between the spaced conductive elements forming the gaps 14, 14' to provide a spark discharge across the gaps which may be employed for internal combustion ignition. Preferably, the gap 14' is shorter than the gap 14 in order to insure that sparking always will occur at the gap 14' which is disposed within the engine cylinder.

Figure 5 is a section of the device described in Figure 4 taken along the section line V-V to illustrate the conformation of the spark gap employed.

Referring to Figures 6 and 7, the device described is similar to Figures 1 and 4 with the exception that a relatively short insulating plug 8 is employed, and ignition is accomplished by heating a metallic element instead of by a spark discharge. An insulating spider 15 disposed transversely of the constricted portion 5 of the ignition plug 1 adjacent the end thereof remote from the enlarged portion 2, supports a conductive ring 16. The conductive ring 16 is resonant

at the operating ignition frequency, and the surface portions thereof are heated to ignition temperatures by circulating currents induced therein by the ignition energy field within the constricted portion of the ignition plug.

At operating frequencies of the order of 10,000 megacycles, the circulating currents penetrate the metallic ring only a few microns, thereby providing extremely high-surface temperatures with relatively low power. Also, as soon as the

ignition energy is interrupted by the distributing device in the ignition pulse generator, the surface temperatures of the conductive ring rapidly decrease due to conduction of the surface heat to the inner body portions of the ring. For example, the ring may be raised to incandescence in a few microseconds and cooled by a conduction to the inner portions thereof in a time interval of the order of 10 microseconds.

It should be understood that the conductive ring which is heated to ignition temperatures may be in any convenient form and of any material providing suitable resistance to corrosion and carbon accumulation. Likewise, the conductive discs providing sparking electrodes in the devices described in Figures 1 to 5 inclusive may be varied in size and shape and constructed of suitable materials to minimize wear and carbon accumulation. It should further be understood that the enlarged portion of the ignition plug may be circular, square or rectangular in cross-section, or of any other shape adapted to receive the particular type of wave guide employed for ignition distribution from the ignition pulse generator.

I claim as my invention:

1. A tuned gas ignition device for ultra-high frequency ignition energy derived from a wave guide energy distribution system comprising a hollow conductive dielectric guide element having a first portion formed to engage said wave guide and having a second portion formed to engage a complementarily shaped utilization device, and conductive ignition means tuned to said frequency and disposed transversely of said device at the end thereof remote from and in operative relation with respect to said hollow con-

ductive element whereby ignition currents are induced in said means in response to ultra-high frequency energy derived from said wave guide.

2. A tuned gas ignition device for ultra-high frequency ignition energy derived from a wave guide energy distribution system comprising a hollow conductive dielectric guide element having a first portion formed to engage said wave guide and having a second portion formed to engage a complementarily shaped utilization device, and conductive ignition means defining a resonant aperture tuned to said frequency and disposed transversely of said device at the end thereof remote from said hollow conductive element to induce in said means an ignition current in response to ultra-high frequency energy derived from said wave guide.

3. A tuned gas ignition device for ultra-high frequency ignition energy derived from a wave guide energy distribution system comprising a hollow conductive dielectric guide element having a first portion formed to engage said wave guide and having a second portion formed to engage a complementarily shaped utilization device, and conductive ignition means tuned to said frequency and disposed transversely of said device at the end thereof remote from said hollow conductive element whereby ignition currents are induced in said means in response to ultra-high frequency energy derived from said wave guide.

4. Apparatus of the type described in claim 1 comprising an ignition plug for an internal combustion device, and including a dielectric element providing a gas seal between said portions of said conductive element to prevent gas leakage from said combustion device through said ignition plug.

5. A tuned gas ignition device for ultra-high frequency ignition energy derived from a wave guide energy distribution system comprising a hollow conductive dielectric guide element having a first portion formed to engage said wave guide and having a second portion formed to en-

gage a complementarily shaped utilization device, and a pair of conductive means spaced an even multiple of one-quarter wavelength and tuned to said frequency and disposed transversely of said device at the end thereof remote from said hollow conductive element to induce in said means an ignition current in response to ultra-high frequency energy derived from said wave guide.

10 5. Apparatus of the type described in claim 5 comprising an ignition plug for an internal combustion device, and including dielectric means interposed between said conductive means and providing a gas seal between said portions of said conductive element to prevent gas leakage from said combustion device through said ignition plug.

15 6. Apparatus of the type described in claim 5 comprising an ignition plug for an internal combustion device, and including dielectric means interposed between said conductive means and providing a gas seal between said portions of said conductive element to prevent gas leakage from said combustion device through said ignition plug.

20 7. A tuned gas ignition device for ultra-high frequency ignition energy derived from a wave guide energy distribution system comprising a hollow conductive dielectric guide element having a first portion formed to engage said wave guide and having a second portion formed to engage a complementarily shaped utilization device, and conductive ignition means defining a current discharge path tuned to said frequency and disposed transversely of said device at the end thereof remote from said hollow conductive element to induce in said means an ignition current in response to ultra-high frequency energy derived from said wave guide.
